UNITED STATES PATENT OFFICE.

PAUL MAUSER, OF OBERNDORF-ON-THE-NECKAR, GERMANY; MARIA JULIE MAUSER, MARIA AGNES SCHNEIDER, MARIA MAGDALENA MAUSER, MAX MAUSER, ANNA WILHELMINE SCHNEIDER, LEONIE DENK, AND ALEXIUS MAUSER, HEIRS OF SAID PAUL MAUSER, DECEASED.

SAFETY DEVICE FOR FIREARMS.

1,150,610.

Specification of Letters Patent. Patented Aug. 17, 1915.

Application filed December 14, 1912. Serial No. 736,797.

To all whom it may concern:

Be it known that I, PAUL MAUSER, a subject of the King of Wurttemberg, residing at Oberndorf-on-the-Neckar, in the Kingdom of Wurttemberg, German Empire, have invented certain new and useful Improvements in Safety Devices for Firearms, of which the following is a specification.

The invention relates to automatic firearms in which the breech-block is supported from behind by locking-levers actuated by means of a recoil operated slide to unlock the breech-block upon recoil of the firearm.

The main object of this invention is to provide improved means for locking the firing mechanism when the locking-levers are in the unlocking position.

Further objects and details of the invention will be set forth hereinafter and 20 pointed out in the claims.

An embodiment of the invention is illustrated in the accompanying drawing, in which:

Figure 1 is a side elevation from the left 25 hand side partly in longitudinal section showing the parts with the breech-block locked in the forward position. Figs. 3, 4 and 5 are respectively an underneath plan, an elevation from the right hand side and a 30 vertical cross section of the parts with the breech-block locked in the rearward position. Figs. 2, 6 and 7 are respectively an underneath plan, an elevation from the right hand side and a vertical cross section 35 showing the breech-block and the firing mechanism locked. Fig. 8 shows a portion of Fig. 3 with the parts in the position immediately after firing.

The breech-block *k* is locked in the known 40 manner by two automatically actuated levers *b* rotatably mounted on the rear wall of the breech-casing. When these levers are set inward (Fig. 2) they support the breech-block from behind and when set outward 45 (Fig. 3) they allow it to pass between them in receding.

Below one of the locking-levers *b* (the

left hand lever in this case) a two-armed lever *p* is pivoted in such a manner as to be capable of oscillation in the horizontal plane 50 on the middle ledge *g*¹ of the casing *g*. The front arm *p*¹ of this lever *p* comprises a nose *p*⁰ which through an opening in the casing *g* engages in a recess *b*⁰ in the locking-lever *b* whereby the lever *p* is positively connected with this locking-lever *b*. The rear arm *p*² of the lever *p* forms a hook *p*³ at its lower part which when the locking-levers *b* are set outward, that is when the breech-block *k* is unlocked, engages 60 with the correspondingly widened hook *z*³ of a lever *z*² pivoted to the trigger *z* and thereby renders it impossible for the trigger to be pulled (Figs. 3 and 5). The trigger can only be pulled when the breech-block *k* is locked. Then the locking-levers *b* are set inward and the locking-lever *b* co-operating with the lever *p* has caused the latter to oscillate so that its locking-hook *p*³ has left the path of the trigger-lever *z*² 70 (Figs. 2 and 7).

The rear arm *p*² of the lever *p* merges at the rear into a finger *p*⁴ which co-operates with a shaft *v* rotatably mounted in the grip-ledge *g*¹. This shaft is provided with 75 a recess *v*¹ in which the finger *p*⁴ of the lever *p* is able to enter (Figs. 3 and 5) so that the latter can oscillate freely with the locking-lever *b*. The shaft *v* can however be rotated by means of the outwardly projecting lever *v*² in such a manner that the lever *p* is unable to enter the recess *v*¹ but its finger *p*⁴ rests upon the solid end face of the shaft *v*. The lever *p* is then unable 80 to oscillate and the breech-block locking-lever *b* is retained in the inwardly rocked position so that the breech-block is locked (Fig. 2).

Two disks *v*³ and *v*⁴ are fixed to the shaft *v* and act upon the breech-block locking-device *a* and the locking device *c* for the sear. The breech-block locking-device *a* presents the form of a one-armed lever rotatably mounted in the vertical plane on the 85 90

grip-ledge g^1 and at its free end it is provided with a forwardly chamfered locking-nose a^1 which in the known manner locks the breech-block in the rearward position when 5 the lever a is moved upward (Fig. 4).

The locking-device c for the sear consists of a two-armed lever rotatably mounted in the vertical plane on the grip-ledge, its front arm c^1 engaging and locking the hook 10 d^1 of the sear d which coöperates with the hook z^3 of the trigger-lever z^2 when the arm c is rocked upward (Fig. 6). The rear arm c^2 of the locking-lever c comprises at its 15 upper part a nose c^3 which is constantly pressed by the spring f against the disk v^3 . This spring f also presses the nose a^2 of the locking-lever a against the disk v^4 . The two disks v^3 and v^4 are provided with recesses 20 v^5 , v^6 and v^7 corresponding to the noses a^2 and c^3 of the locking-levers a and c .

If the adjusting-lever v^2 is set horizontally (Figs. 1, 3, 4 and 5) the nose a^2 of the breech-block locking-lever a is located in the recess v^7 of the disk v^4 and the nose c^3 of 25 the sear locking-lever c is located in the recess v^5 in the disk v^3 . The breech-block locking-lever a is therefore operative, the sear locking-lever c inoperative and the lever p rotatable with the locking-lever b . 30 The weapon is consequently set for single firing.

If repeating firing is desired the adjusting-lever v^2 is rotated to the median position in which the nose a^2 of the breech-block 35 locking-lever a rests on the periphery of the disk v^4 and the nose c^3 of the sear locking-lever c in the recess v^6 in the disk v^3 . The locking-levers a and c are now inoperative and the lever p is movable with the breech-block locking-lever b .

If the adjusting-lever v^2 is caused to occupy the vertical position (Figs. 2, 6 and 7) the noses a^2 and c^3 of the locking-levers a and c rest on the periphery of the disks v^3 45 and v^4 . The breech-block locking-lever a is then inoperative, the sear locking-lever c operative and the lever p locked in the position in which the breech-block is locked in the forward position by the locking-levers b . 50 The weapon is therefore set at safety and the breech mechanism and the trigger mechanism are both locked. The lever p also serves to interrupt the engagement between the sear d and the trigger-lever z^2 immediately after firing in order to prevent recurrent firing. If the trigger has only been pulled to such an extent that although the striking-pin has been released the hook z^3 of the trigger-lever z^2 still engages with the 55 hook d^1 of the sear, the rear chamfered face of the hook p^3 of the lever p which has been rocked outward on recoil by the locking-lever b encounters the hook z^3 and pushes it

retractively so that the trigger-lever z^2 is rotated rearward and thus released from the 65 sear (Fig. 3). The sear is therefore at once free for engaging the firing-pin.

What I claim as my invention and desire to secure by Letters Patent is:—

1. In an automatic firearm, the combination of a breech-block, locking-levers for said breech-block, recoil operated means for actuating said locking-levers, firing mechanism, and means automatically locking said firing mechanism when said locking-levers 75 are in the unlocking position comprising a pivoted two-armed lever having one arm positively connected with one of said breech-block locking-levers and the other arm co-operating with said firing mechanism. 80

2. In an automatic firearm, the combination of a breech-block, locking-levers for said breech-block, recoil operated means for actuating said locking-levers, firing mechanism comprising a trigger, a sear and a 85 lever pivoted to said trigger and coöperating with said sear, and means automatically locking said firing mechanism when said breech-block locking-levers are in the unlocking position comprising a pivoted two- 90 armed lever having one arm positively connected with one of said breech-block locking-levers and the other arm adapted to engage said trigger-lever.

3. In an automatic firearm, the combination of a breech-block, locking-levers therefor, means for actuating said locking-levers upon recoil to unlock said breech-block, firing mechanism comprising a trigger and a sear, means controlled by 100 said breech-block locking-levers automatically locking said trigger when said breech-block is in its open position, and manually adjusted means for locking said sear and adapted to lock said trigger locking means 105 in the position in which said breech-block is locked by its locking-levers.

4. In an automatic firearm, the combination of a breech-block, locking-levers therefor, means for actuating said locking-levers 110 upon recoil to unlock said breech-block, firing mechanism comprising a trigger and a sear, a lever controlled by one of said breech-block locking-levers automatically locking said trigger when said breech-block 115 is in its open position, and manually operated means for locking said sear comprising a part having a recess allowing the rocking of said trigger locking-lever in the locking position when said sear locking means is in 120 its inoperative position and an abutment preventing the rocking of said trigger locking-lever in the locking position when said sear locking-lever is in its locking position thereby locking said breech-block locking-levers in the locking position. 125

5. In an automatic firearm, the combination of a breech-block, locking levers therefore, means for actuating said locking levers upon recoil to unlock said breech-block, 5 firing mechanism comprising a trigger and a sear, means controlled by said breech-block locking levers adapted to automatically lock said trigger when said breech-block is in its open position, and to disen-

gage said trigger from said sear immediately after firing.

In testimony whereof I have affixed my signature in presence of two witnesses.

PAUL MAUSER.
